UNITED STATES PATENT OFFICE.

LUDWIG KÜHN, OF BERLIN-CHARLOTTENBURG, GERMANY, ASSIGNEE TO WESTINGHOUSE ELECTRIC & MANUFACTURING COMPANY, A CORPORATION OF PENNSYLVANIA.

COMBINED TRANSMITTING AND RECEIVING ARRANGEMENT.

Application filed August 26, 1921. Serial No. 495,739.

To all whom it may concern:

Be it known that I, LUDWIG KÜHN, a subject of the Republic of Germany, residing at 103 Kaiser-Friedrichstrasse, Berlin-Charlottenburg, Germany, have invented certain new and useful Improvements in Combined Transmitting and Receiving Arrangement (for which applicant has filed in the following countries—Germany, December 14, 1917, 10 and December 15, 1917; Great Britain, July 12, 1920; France, July 30, 1920; Denmark, April 16, 1920; Holland, March 5, 1920; Sweden, January 3, 1920), of which the following is a specification.

15 The present invention relates to wave signalling systems and has for its object the provision of a system employing vacuum tubes, which is particularly adapted for reception of continuous wave signals and 20 which may by simple changes of connections be used for the transmission of continuous waves, audio frequency modulated continuous waves or voice modulated continuous waves.

25 The invention further comprises various features hereinafter more particularly pointed out with reference to the accompanying drawing in which a preferred embodiment is illustrated, the circuit as shown being arranged for reception.

30 Referring now to the drawing, an antenna 6 is coupled to the plate circuit of a vacuum tube 1 by means of the variable inductance 5, a portion of which is common to both the 35 plate circuit of the vacuum tube 1 and the antenna circuit. The antenna circuit may be conveniently tuned by means of the variable inductance 5 or the variable inductance 7 which is included in the antenna circuit although any other commonly employed 40 tuning arrangement may be utilized. Inasmuch as in the embodiment shown, the coupling between the plate circuit of the tube 1 and the antenna circuit is varied by relative 45 adjustments of the amount of inductance 5 in each of the circuits, the variable inductance 7 is convenient in tuning the antenna circuit.

50 The plate circuit of tube 1 includes besides the variable inductance 5, the primary 10 of a transformer 11 and a battery 8 or other source of potential. It is desired that the battery and the transformer primary be shunted by condensers 9 and 12 respectively

and the applied potential of the battery be 55 made variable by means such as a switch 13. The grid circuit of the tube 1 may be also tuned to any desired frequency by means of the variable condenser 18 which is in parallel with the inductance 17. A condenser 19 60 in this circuit is shunted by the secondary of a transformer 21, the leads to which are arranged so they may be disconnected at any convenient points such as 37. In order to control the grid bias potential the grid circuit is connected to the filament by a lead 16 65 contacting with a resistance element 15 in the filament circuit. This resistance element also serves to control the current from the battery 14 through the filament 4.

70 The plate circuit of a second vacuum tube 22 includes the primary of the transformer 21 and is thus coupled to the grid circuit of tube 1. The primary 23 of another transformer 24 is in the plate circuit of tube 22 75 and switching means are also included whereby the circuit may be interrupted at any convenient points as at 36.

As shown, the plate potential of the tube 22 may be obtained from the battery 8 and 80 the filament current from the battery 14, a resistor 29, preferably of iron wire, being included in the filament circuit to limit the current.

85 A third vacuum tube 32 may be provided, the plate circuit of which includes the indicating device 35, and the battery 8, and the grid circuit of which includes the secondary of the transformer 24 and is thereby coupled to the plate circuit of tube 22. The filament 90 33 of tube 32 may be connected as shown so as to be heated from the battery 14, a resistor 34 being in circuit to limit the current.

95 As illustrated, the connections are arranged for the reception of continuous wave signals by the heterodyne method. The grid and plate circuits of tube 1 may be tuned so that the tube 1 will oscillate at a frequency slightly different from the frequency of the signal to be received. The 100 continuous waves received by the antenna system will then combine with the continuous waves produced by the local oscillator, resulting in the well known beat note of 105 audible frequency. The oscillations of beat note frequency are conducted through the transformer 11 to the grid of the vacuum tube 22, which produces an amplified oscil-

lation in its plate circuit. To obtain a feedback action, this plate circuit is coupled by transformer 21 to the grid circuit of tube 1 so that the tube 1 will act as an amplifier 5 transferring the energy again from its plate circuit to the grid circuit of tube 22. The plate circuit of tube 22 also contains the primary of transformer 24, the secondary of which is in the grid circuit of tube 32. This 10 tube further amplifies the signals which are received by the indicating device, preferably a telephone, 35, which is in the plate circuit of this tube.

By changing a few connections of this receiving circuit, the apparatus may be adapted for use as a transmitter of either continuous waves, modulated continuous waves or speech.

For the transmission of continuous wave 20 signals, the transformer 21 is cut out of circuit by either bridging across it or opening the leads at 37 by means of a switch. It is advisable to positively render the tube 22 inoperative by opening its plate circuit at 36. 25 With these changes the plate and grid circuits of tube 1 and the antenna circuit may be adjusted to the desired transmitting frequency and the energy for radiation will be supplied thereto, as will be readily understood by those skilled in the art. In order to interrupt the transmission in accordance with the signals to be sent out a key may be provided in the antenna circuit so as to interrupt the circuit or a key in parallel 30 with an inductance may be coupled to any of the circuits to change the frequency of that circuit thus controlling the oscillation of the tube. These methods form no part of this invention and are so well known that 35 it is unnecessary to illustrate them.

If modulated continuous waves are to be transmitted the inductance 20 is included in the grid circuit of tube 1 by closing the switches 37, so that an oscillating circuit of 40 audible frequency is formed by the inductance 20 and condenser 19. As is well known these audible frequency oscillations will be impressed on the super-audible frequency oscillations in the oscillating grid circuit so 45 as to modulate them at an audible frequency. The audible frequency oscillations will be changed in frequency by variations in either condenser 19 or inductance 20 and it is preferred that the inductance 20 be made 50 variable.

The superaudible frequency or carrier 55 wave oscillations may be varied in frequency in the usual manner by adjustments of condenser 18 and corresponding adjustments of plate and antenna circuits.

In order to transmit speech, a microphone 60 38 and battery 39 may be coupled to the grid circuit of tube 1, preferably by means of transformer 21, the battery and microphone being inserted in the primary circuit 65

by connecting leads 40 and 41 across the transformer primary as indicated on the drawing.

When these changes are made for transmission, tubes 22 and 32 are not used and 70 the filament 28 and 33 may be cut out of circuit. The switch 13 may be thrown so that the full potential of the battery 8 is applied to the plate circuit of tube 1.

In order to avoid undesirable audio frequency oscillations in the system it has been found desirable to have all the transformers of the same ratio and to connect them in circuit so that the current flows in the same direction through the primary and secondary. The adjustable slider 16 may be varied to control the grid bias potential to stabilize the system for prevention of undesirable oscillations. 75

In transmission best results are obtained 80 with a particular coupling between the plate circuit of tube 1 and antenna 6. This coupling may be varied by independently adjusting the amount of inductance 5 in each circuit and the antenna system may be tuned 85 with variable inductance 7. Inasmuch as the coupling is not as important during reception as during transmission, and is usually about the same in both cases, it is not necessary to change the coupling for reception 90 and it may be left at the value which is found to be best for transmission. 95

In order to further simplify the operation of the apparatus the controls for the antenna circuit and grid circuit may be mechanically 100 connected so that changes in the circuits are made simultaneously by manipulation of only one control.

It is to be understood that the foregoing 105 description of a preferred embodiment is not to at all limit the spirit or scope of this invention as various modifications will be apparent to those skilled in the art.

I claim:

1. In a radio communication system, an 110 antenna, a vacuum tube, circuits associated with said tube to cause it to function as both an oscillator and a detector, said associated circuits including a coupling to the antenna, a grid circuit and a circuit coupled to the antenna and to the grid circuit, an amplifier in said coupled circuit, an indicating device associated with said coupled circuit, and switching means for opening said coupled circuit, whereby when said coupled circuit is closed, signals may be received by heterodyne reception and when said switching means are open, said vacuum tube may function as a transmitter of continuous 115 waves. 120

2. In a radio communication system, an 125 antenna, a vacuum tube, circuits associated with said tube to cause it to function as both an oscillator and a detector, said associated circuits including a plate circuit coupled to 130

- the antenna, a grid circuit, an audio-frequency oscillating circuit in said grid circuit, and a circuit coupled to the antenna and to the grid circuit, an indicating device 5 associated with said coupled circuit, and switching means for opening said coupled circuit, whereby when said coupled circuit is closed, signals may be received by heterodyne reception and when said switching 10 means are open, said vacuum tube may function as a transmitter of modulated continuous waves and switching devices for rendering inoperative said audio-frequency oscillating circuit whereby said transmitter may 15 be caused to deliver unmodulated waves.
3. In a radio communication system, an antenna, a vacuum tube oscillator and detector comprising a grid circuit which includes an audio frequency oscillating circuit and a 20 plate circuit coupled to said antenna, a vacuum tube repeater comprising a plate circuit coupled to the grid circuit of said oscillator and detector tube and a grid circuit coupled to the plate circuit of said oscillator and detector 25 tube whereby received continuous waves are impressed upon the oscillator and detector tube for heterodyne reception, an amplifying circuit, including indicating means, coupled to said tube repeater circuit, switching means for disconnecting said repeater circuit and associated indicating device 30 whereby said oscillator tube is rendered operative as a transmitter of modulated continuous waves, switching means for cutting out said audio frequency oscillating circuit from the grid circuit of said oscillator tube 35 to render said oscillator operative as a transmitter of continuous waves and switching means for connecting said microphone to said oscillator to render said oscillator operative as a continuous wave telephone 40 45 50 55 60 65 transmitter.

In testimony whereof I affix my signature.

DR. INC. LUDWIG KUHN.
